UNITED STATES PATENT OFFICE.

LEON M. GIROUX, OF NEW YORK, N. Y.

DESIGN FOR AN AUTOMOBILE-LAMP.

48,176.

Specification for Design.

Patented Nov. 23, 1915.

Application filed May 3, 1915. Serial No. 25,613. Term of patent 3½ years.

To all whom it may concern:

Be it known that I, LEON M. GIROUX, a citizen of the United States, residing at New York, in the borough of Manhattan, county of New York, and State of New York, have invented a new, original, and ornamental Design for Automobile-Lamps, of which the following is a specification, reference being had to the accompanying drawing, forming part thereof.

In the drawing, Figure 1 is a side elevation of a lamp embodying my improved ornamental design. The general configuration of the lamp is bullet-shaped, the point be-

ing toward the rear, a lens being inserted in the large end and a piece of colored glass in the point. The cylindrical portion of the same is provided circumferentially with a plurality of longitudinally disposed openings, in which are inserted pieces of red glass. Fig. 2 is a front view of the same.

I claim:—

The ornamental design for an automobile lamp, as shown and described.

LEON M. GIROUX.
